US00D607907S

(12) **United States Design Patent**
de Malherbe

(10) **Patent No.:** **US D607,907 S**
(45) **Date of Patent:** **** Jan. 12, 2010**

(54) **REFRIGERATING UNIT**

(75) Inventor: **Hubert de Malherbe**, Paris (FR)

D589,538 S * 3/2009 Kumazawa et al. D15/81

(73) Assignee: **AHT Cooling Systems GmbH**,
Rottenmann (AT)

* cited by examiner

(**) Term: **14 Years**

Primary Examiner—Stella M Reid

Assistant Examiner—Shanda C Hill

(74) Attorney, Agent, or Firm—Fross Zelnick Lehrman & Zissu, P.C.; Charles T. J. Weigell, Esq.

(21) Appl. No.: **29/292,756**

(57) **CLAIM**

(22) Filed: **Oct. 25, 2007**

The ornamental design for a refrigerating unit, as shown and described.

(51) **LOC (9) Cl.** **15-07**

DESCRIPTION

(52) **U.S. Cl.** **D15/83; D15/79**

FIG. 1 is a perspective view of a refrigerating unit showing the new design;

(58) **Field of Classification Search** **D15/79,**
D15/81, 83, 84, 85; 62/3.6, 3.63, 3.64, 246–257;
312/236, 400–408; D6/437, 470, 471, 473

FIG. 2 is a front view of the refrigerating unit shown in FIG. 1;

See application file for complete search history.

FIG. 3 is a rear view of the refrigerating unit shown in FIG. 1;

FIG. 4 is a left side view of the refrigerating unit shown in FIG. 1;

FIG. 5 is a right side view of the refrigerating unit shown in FIG. 1; and,

FIG. 6 is a top view of the refrigerating unit shown in FIG. 1.
The broken line showing of the rear utility panel is for illustrative purposes only and forms no part of the claimed design.
